Primary Examiner — Karen E Kearney*Assistant Examiner* — Haley K Schnebele(57) **CLAIM**

The ornamental design for a bottle as shown and described.

DESCRIPTION

FIG. 1 is a perspective view of a bottle, in accordance with our new design;

FIG. 2 is a left side view thereof;

FIG. 3 is a right side view thereof;

FIG. 4 is a front elevational view thereof;

FIG. 5 is a back elevational view thereof;

FIG. 6 is a top view thereof; and,

FIG. 7 is a bottom view thereof.

The dash-dash broken lines shown illustrate portions of the bottle that form no part of the claimed design.

1 Claim, 7 Drawing Sheets(56)
